UNITED STATES PATENT OFFICE.

CHARLES W. HUTCHINSON, OF NEW YORK, N. Y.

BOSOM-SHIRT CONSTRUCTION.

Application filed November 9, 1925. Serial No. 67,941.

This invention relates to garments and has particular reference to certain improvements in the construction of men's stiff bosom dress shirts.

5 Stiff bosom dress shirts as now commonly constructed have the bosoms stitched or otherwise secured to the body of the shirt completely around the marginal edges of the bosom, and in practice when constructed 10 in this manner they are open to the objection of the tendency of the bosom to "break" or "buckle" when the wearer assumes a sitting posture. Furthermore, and especially in ready-made shirts, it is impossible to devise 15 a standard size of bosom which will properly fit the wearer with an appreciable degree of comfort, and this in addition to the difficulty generally experienced in buttoning the shirt or applying the studs thereto.

In order to overcome the above-recited disadvantages and objections, the present invention comprehends as its principal object a stiff bosom dress shirt construction of 25 either the coat type or rear-button type, in which the side and lower edges of the bosom are free from the flexible body of the shirt and in which said bosom is secured only along a substantially medial line to the center of the front of the shirt body and at its 30 upper edges to the neckband and yoke.

The invention furthermore comprehends a stiff bosom dress shirt construction which is comparatively simple, highly efficient in 35 its purpose, and which, if anything, effects a substantial economy in the manufacture of shirts of this character.

With the above recited and other objects in view, reference is had to the following 40 specification and accompanying drawings, in which there is exhibited one example or embodiment of the invention which is in no way intended as a limitation upon the scope of the appended claims as it is to be clearly 45 understood that variations and modifications which properly fall within the scope of said claims may be resorted to when found expedient.

In the drawing—

50 Figure 1 is a front view of a shirt constructed in accordance with the invention;

Fig. 2 is a horizontal fragmentary sectional view therethrough taken approximately on the line indicated at 2-2 in 55 Fig. 1;

Fig. 3 is a fragmentary inside view of

the lower portion of the shirt with the front edges in opened condition.

Referring to the drawing by characters of reference, 10 designates the body of the 60 shirt, including the usual neckband 11, yoke 12 and sleeves 13, the body having the usual overlapping inner and outer front edges 14 and 15. The bosom includes the inner and outer overlapping sections 16 and 17, the 65 latter being secured by a line of stitching 18 to the inner margin of the outer edge 15 of the shirt body 10, said line of stitching terminating an appreciable distance above the lower end of the bosom section. The 70 upper edges of the bosom are secured respectively by lines of stitching 19 and 20 to the neckband and yoke, while the remaining free marginal edges of the bosom section are 75 free from the shirt body.

The bosom and edge 15 adjacent their points of securement by the line of stitching 18, are formed with buttonholes 21 worked completely through the bosom section and the edge 15. The inner bosom section 16 is 80 secured by a line of stitching 22 to the inner margin of the inner overlapped edge 14 of the shirt body, which line of stitching terminates an appreciable distance above the lower end of the bosom section and which 85 extends to the neckband 11.

The upper edges of the bosom section 16 are secured respectively by lines of stitching 23 and 24 to the neckband and yoke, 90 while the remaining marginal edges are free from the shirt body. The bosom section 16 has buttonholes 25 worked therethrough adjacent the line of stitching 22, but said buttonholes are not worked through the edge 95 14 of the shirt body.

To ensure the proper overlapping relation of the bosom sections 16 and 17 at their lower free ends and to permit them in such relation to pass over the outer surface of the trousers, the inner edge of the body member 100 15 is cut out on a re-entrant curve from the lower end of the stitching which secures it to the bosom section 17, while the companion edge of the body member 14 is made with a complementary mating extension, as 105 illustrated more plainly in Figure 3; the width of the cut out should be not less than the width of the overlap of the bosom sections.

From this construction it is obvious that 110 in practice the shirt body will hold and maintain the bosom in properly applied posi-

tion while the lower end of the bosom section may be disposed exteriorly of the front of the trousers to preclude "buckling" or "breaking" of the bosom when the wearer 5 either stoops over or assumes a sitting posture. The free side edges also eliminate the possibility of lateral "bending" or "buckling" of the bosom as is the case where the side edges of the same are stitched to the 10 body.

It will further be noted that the application and buttoning of the studs is greatly facilitated due to the fact that the hand 15 may be inserted between the bosom section 16 and the shirt body from the side edge to manipulate the button or stud.

What is claimed is:

1. In a dress shirt construction, a flexible body and a stiff bosom including a pair 20 of sections, each section secured at its inner edge to an overlapped edge of the front of the body and at its upper edge to the neckband of the shirt with the outer side edge of the innermost bosom section 25 free from the body, the outermost overlapped section having buttonholes extending through the same and through the shirt body adjacent its juncture with the bosom and the innermost overlapped section having 30 buttonholes extending only through said bosom section to facilitate the buttoning of the studs by the insertion of the hand between the bosom and shirt body from the free side edge of the innermost bosom section. 35

2. A dress shirt construction including a flexible body of the coat type having over-

lapping front edges and relatively stiff bosom sections having their upper edge portions secured to the overlapped edges of the shirt body by stitching extending from points above the lower ends of the bosom sections to the neckband and having their upper edge portions secured to the neckband of the shirt, the remaining marginal 45 edges of the innermost bosom section being free, the outermost bosom section and overlapped edge of the shirt body having buttonholes worked completely therethrough and the innermost bosom section having buttonholes worked through said bosom section only, as and for the purposes specified. 50

3. A dress shirt construction including a flexible body of the coat type having overlapping front edges and relatively stiff bosom sections secured to the overlapped edges of the shirt body by stitching extending from points above the lower ends of the bosom sections to the neckband of the shirt, the edge portion of the outermost body section being cut away from approximately the lower end of the stitching securing the respective body and bosom sections together, and the other body section having a complementary mating extension, whereby to ensure proper overlapping relation of the bosom sections and to permit the lower free ends of such sections in such overlapped relation to pass outwardly over the outer surface of the trousers, as and for the purpose specified. 55 60 65 70
